DRAUGHT REGULATOR

Frank L. Trethewey, Toronto, Ontario, Canada

Application March 12, 1934, Serial No. 715,040

8 Claims. (Cl. 236—93)

This invention relates to means for automatically controlling the draught of fuel burning stoves and furnaces, and my object is to devise an automatic regulator, operative by controlling the flow 5 of the flue gases from the furnace, which will be very sensitive, which will have a wide range, which will be durable and efficient and which will be responsive to varying outside temperatures.

10 I attain my object by means which may be briefly described as follows. A thermostatic element is positioned in a flue through which pass the products of combustion from the furnace. With this flue at the furnace side of the thermostatic element communicates an inlet for atmospheric air which is provided with a damper controlled by said element. Thus, when the damper is partly or wholly open, the thermostatic element is exposed to a mixture of the flue gases and 15 cooler atmospheric air, which mixture is subject to much greater changes of temperature than the flue gases themselves, so that the movements of the thermostatic element are much greater than if it were affected by the flue gases alone. 20 And more accurate regulation of the damper results. A second damper is preferably positioned in the flue between the air inlet and the furnace which is actuated by the thermostatic element simultaneously with the first mentioned damper. 25 The inlet for atmospheric air is optionally piped to communicate with the air outside the building. Thus the draught control is made responsive to the load imposed on the heater by temperature of the outside air, or inside air as the case may be, 30 according as room air or outside air is acting on the thermostatic element.

35 Further features of the invention will hereinafter appear and the whole is hereinafter more fully described and is illustrated in the accompanying drawing in which

Fig. 1 is a side elevation of my draught regulator, partly broken away;

Fig. 2 a plan view of the same; and

Fig. 3 a longitudinal sectional detail of the 40 thermostatic element and its mounting.

In the drawing like numerals of reference indicate corresponding parts in the different figures.

45 Referring to the drawing, 1 is a smoke flue, which is shown as a pipe adapted to be connected with the smoke outlet of a stove or furnace. In the side of this flue is an opening 3 with which communicates an air flue 2. This air flue 50 communicates with the atmospheric in the chamber in which the heater is located, but may, of course,

be extended to communicate with the outside air.

The passage of air through the opening 3 is controlled by means of the butterfly damper 4, which is secured to a spindle 5 journalled in the walls of the flue. This damper thus controls the admission of cold air to the interior of the flue 1. Within the flue 1 at that side of the opening 3 which is nearest the heater with which the flue 1 is connected is positioned the butterfly damper 10 6 which is connected to the spindle 7 journalled in the walls of the flue.

The spindle 5 is provided with the crank arm 8 and the spindle 7 with the crank arm 9. To these crank arms is pivotally connected the connecting rod 10 so that the dampers may be actuated simultaneously.

In the full draught position it will be noted that the damper 6 will be positioned longitudinally of the flue 1 and the damper 4 transversely of the 20 flue 2, while in the minimum draught position the position of these dampers is reversed.

The dampers are actuated by a thermostatic element which is positioned in the flue 1 at that side of the opening 3 which is remote from the heater with which the flue 1 is connected. Thus the thermostat will be exposed not only to the heated flue gases, but also to the effect of cold air admitted through the opening 3.

The thermostatic element comprises a supporting member 11, which is secured to the side of the flue by means of the bolts 12. This supporting member closes an opening in the side of the flue 1 which is of a size adequate for the passage of the parts of the thermostatic element which are required to be positioned within the flue. In the supporting member is journalled an anchor member 13 and within the anchor member is journalled the spindle 14. A thermostatic coil 15 of the usual bi-metallic type has one end secured 40 to the spindle and the other end secured to the anchor member. If the anchor member be held from rotating then the expansion and contraction of the thermostatic coil will rotate the spindle 14.

To the outer end of the spindle 14 is secured or 45 formed the crank arm 18, which crank arm is pivotally connected to one end of the connecting rod 23, the other end of which is pivotally connected with the crank arm 9 of the spindle 7 of the damper 6. Simultaneous operation of the 50 dampers 4 and 6 is thus obtained from the one thermostatic element.

The anchor member 13 is rotatably adjustable so that the thermostatic element may be set to cause it to move the dampers to the substan- 55

tially no draught position at a predetermined temperature of the gases to which the thermostatic element is subjected. For this purpose I provide the anchor member with the hand wheel 16 by means of which it is rotated. Preferably the anchor member is held in the position to which it is adjusted by frictional rather than positive means, and for this purpose I provide the brake plunger 20 slideable in the supporting member 11 and engaging the anchor member.

The outer end of the plunger is slideable in the pointer 17, which serves as an indicator to show the setting of the anchor member. A coil spring 21 bears against the pointer and against an abutment pin 22 passed through the plunger 20. The friction of the plunger is sufficient to hold the outer member stationary in any position to which it has been turned, while the anchor member may slip to avoid straining of the thermostatic coil if the latter be overheated. The end of the plunger fits into a groove in the anchor member and thus holds it from endwise displacement.

The mode of operation is as follows. With a cold flue the dampers will be in such a position that the maximum desired opening of the flue 1 and the minimum desired opening of the flue 2 is obtained. When a fire is made up in the heater the flue gases become warm and the thermostatic element then operates to move the dampers to check the draft. This immediately admits more cold air to mix with the flue gases and thus cools the thermostat and prevents an undue choking down of the draught. If the fire remains steady the apparatus soon attains a position of equilibrium. If the fire increases unduly the dampers are progressively actuated to check the draught till their maximum check position is reached. If the air inlet is piped to the outside air the device is sensitive to outside air conditions and draught is increased as outside temperatures fall and vice versa.

The maximum temperature necessary in the mixture of air and flue gases impinging on the thermostatic coil before the dampers will be moved to the full check position is regulated by adjusting the anchor member. The dampers are stopped from passing the full draught position by the engagement of the end 19 of the crank arm 18 with the underside of the connecting rod 10 which avoids the use of stops within the flues.

It will be noted also that the thermostatic element is readily removable for cleaning by lifting the plunger 20 and withdrawing the element through the opening in the supporting member.

While the thermostatic element preferred is of the type shown it will be understood that other known forms might be substituted in broad embodiments of the invention.

From the above description it will be seen that I have devised an automatic draught control which will satisfactorily attain the objects of my invention as hereinbefore set forth.

What I claim as my invention is:

1. In an automatic damper, the combination with a flue having an inlet for atmospheric air, of a thermostatic element positioned in the flue in the path of flue gases and of air entering the opening in the flue under the influence of flue gases travelling through the flue comprising a thermostatic coil, a spindle passing through the flue wall and to which one end of the coil is secured, and an anchor member carried by the flue wall and to which the other end of the coil is secured; means for rotatably adjusting the anchor member; a crank arm on the spindle; a pivoted

damper; a crank arm connected with the damper; and a connecting rod pivotally connected with the crank arms.

2. In an automatic damper, the combination with a flue having an inlet for atmospheric air, of a thermostatic element positioned in the flue in the path of flue gases and of air entering the opening in the flue under the influence of flue gases travelling through the flue comprising a thermostatic coil, a spindle passing through the flue wall and to which one end of the coil is secured, and an anchor member carried by the flue wall and to which the other end of the coil is secured; a crank arm on the spindle; a damper pivoted in the air opening; a crank arm connected with said damper; a damper pivoted in the flue; a crank arm connected with said damper; a connecting rod pivotally connecting the damper crank arm; and a connecting rod pivotally connected with the crank arm of one damper and the crank arm on the spindle.

3. In an automatic damper, the combination with a flue having an inlet for atmospheric air, of a thermostatic element positioned in the flue in the path of flue gases and of air entering the opening in the flue under the influence of flue gases travelling through the flue comprising a thermostatic coil, a spindle passing through the flue wall and to which one end of the coil is secured, and an anchor member carried by the flue wall and to which the other end of the coil is secured; a friction brake yieldingly resisting the rotation of the anchor member; a crank arm on the spindle; a pivoted damper; a crank arm connected with the damper; and a connecting rod pivotally connected with the crank arms.

4. In an automatic damper, the combination with a flue having an inlet for atmospheric air, of a thermostatic element positioned in the flue in the path of flue gases and of air entering the opening in the flue under the influence of flue gases travelling through the flue comprising a thermostatic coil, a spindle passing through the flue wall and to which one end of the coil is secured, and an anchor member carried by the flue wall and to which the other end of the coil is secured; a crank arm on the spindle; a damper pivoted in the air opening; a crank arm connected with said damper; a damper pivoted in the flue; a crank arm connected with said damper; a connecting rod pivotally connecting the damper crank arm; a connecting rod pivotally connected to the crank arm on the spindle and the crank arm of the flue damper; and a projecting part on the spindle crank arm engageable with the connecting rod aforesaid to form a stop defining the full draft position of the dampers.

5. In an automatic damper, the combination with communicating flues each having a damper therein; crank arms connected respectively with the dampers; a thermostatic element in one flue; a spindle journaled in the last mentioned flue operable by the said element; a crank arm on the spindle; a connecting rod pivotally connected with the crank arms of the dampers; and a connecting rod pivotally connected with the spindle crank arm and one of the damper crank arms.

6. In an automatic damper, the combination with a flue having an opening therein for the passage of a thermostatic element; a supporting member for a thermostatic element detachably secured to the flue wall about said opening; and a thermostatic element comprising a thermostatic coil located in the flue, an anchor member journaled in the supporting member, a spindle jour-

nalled in the anchor member, and means for rotatively adjusting the anchor member relative to the supporting member, the coil being secured at opposite ends to the spindle and anchor member; and a damper operable by the spindle.

7. In an automatic damper, the combination with a flue having an opening therein for the passage of a thermostatic element; a supporting member for a thermostatic element detachably secured to the flue wall about said opening; a thermostatic element comprising a thermostatic coil located in the flue, an anchor member journaled in the supporting member, a spindle journaled in the anchor member, and a friction brake yieldingly resisting relative movement of the anchor member relative to the supporting member,

the coil being secured at opposite ends to the spindle and anchor member; and a damper operable by the spindle.

8. In an automatic damper, the combination with a flue having an opening therein for the passage of a thermostatic element; a supporting member for a thermostatic element detachably secured to the flue wall about said opening; a thermostatic element comprising a thermostatic coil located in the flue, an anchor member closing the opening aforesaid and releasably held therein, a spindle journaled in the anchor member, the coil being secured at opposite ends to the spindle and anchor member; and a damper operable by the spindle.

FRANK L. TRETHEWEY.
